ATTORNEY

UNITED STATES PATENT OFFICE.

NESRALLA JOHNS, OF SAN JOSE, CALIFORNIA.

DESIGN FOR A SAVINGS-BANK.

52,824.

Specification for Design.

Patented Dec. 31, 1918.

Application filed October 14, 1918. Serial No. 258,120. Term of patent 7 years.

To all whom it may concern:

Be it known that I, NESRALLA JOHNS, a citizen of the United States, residing at San Jose, in the county of Santa Clara and State of California, have invented a new, original, and ornamental Design for a Savings-Bank, of which the following is a specification, reference being had to the accompanying drawing, forming a part thereof.

The figure is a perspective view of a savings bank showing my new design, with coin slot at A.

I claim:

The ornamental design for a savings-bank, as shown.

NESRALLA JOHNS.
